AUTOMATIC WAX MAT

Henry A. Andresen and Roy R. Stade,
Fairmont, Minn.

Application August 10, 1948, Serial No. 43,466

2 Claims. (Cl. 91—54.7)

1

This invention relates to mats and the like, and particularly to an automatic dispensing mat for dispensing or applying comminuted and/or waxy material to the sole of a shoe brought into contact with the mat.

The main object of our invention is to provide a special dispensing mat of the indicated character which contains a charge of material such as powdered wax adapted to be dispensed by the mat and applied thereby to the soles of shoes of a person who steps on or wipes the feet on the mat.

Another object is to provide such a dispensing mat which may be charged or renewed with a fresh charge of powdered wax when the original charge is exhausted.

A further object is to have such a wax-dispensing mat which primarily forms a container for the wax to be dispensed and likewise a stationary applicator for applying the wax dispensed thereby, and which in addition has a fabric cover or envelope for concealing the true nature of the mat and even providing an ornamental appearance therefor.

It is also an object to produce a dispensing mat or applicator as indicated which may be made of rubber, plastic or other resilient or partly resilient material perforated upon the upper side beneath the fabric cover while internally supported in a resilient manner to maintain the mat in proper form and operative condition.

Other objects and advantages of the invention will appear in further detail as the specification proceeds.

In order to facilitate ready comprehension of this invention, for a proper appreciation of the salient features thereof, the invention is illustrated on the accompanying drawing forming part hereof, and in which:

Figure 1 is a plan view of a mat made according to the invention and embodying the same in a practical form;

Figure 2 is a longitudinal section taken on line 2—2 in Figure 1;

Figure 3 is a fragmentary bottom plan view of the mat with a portion of the cover removed to disclose details.

In the views the same reference numerals indicate the same or like parts.

In ballrooms or dancing pavilions and the like, it is frequently the case that the floor is either too dry and sticky or slippery, due to the lack of wax or too much wax. The partial lack of wax or excess thereof on a floor is often due to poor judgment on the part of the attendants who mis-

judge the proper amount to be applied to the floor so that it will smoothly support foot movements without being slippery.

In view of this situation, it has occurred to us that the proper amount of wax is at least partly a matter of personal opinion, and if left to the individual will likely result in complete satisfaction to all concerned. Thus, after due consideration of this problem, we have succeeded in producing a special wax-dispensing mat for individual use by which each person may apply just the right amount of wax to the sole of the shoe instead of any generous waxing of the floor, as will now be particularly described.

Hence, in the practice of our invention, and referring again to the drawing, a substantially rectangular dispensing mat or wax applicator, generally indicated at 4, includes an internal container, generally indicated at 5, consisting of a flat bottom 6, peripheral walls 7, 8 projecting upwardly and integrally from the bottom 6 and connecting integrally with a top 9 which is parallel to the bottom 6 and pierced at regular intervals over its entire surface by a plurality of dispensing apertures 10, 10, etc. The container including the bottom and the marginal walls 7, 8, etc., as well as the top, is preferably made of semi-resilient grade of rubber, plastic or the like while the interior space 11 between the upper wall or top 9 and the bottom 6 is preferably filled with powdered wax 12.

In order to maintain the chamber 11 in proper form and prevent the top 9 from collapsing either from its own weight or from the weight of a person momentarily standing upon the mat, a large number of supporting springs 13, 13, etc., are distributed between the bottom 6 and the top 9 at regular intervals intermediate the apertures 10, 10 in such fashion that the entire top is thus supported and will resume its elevated parallel condition with respect to the bottom 6 immediately upon release thereof by the person using the mat by removing his shoes therefrom, and thereby ensuring that the mat will remain in perfectly flat condition with a presentable appearance. In order to fix the springs in proper position, each spring is provided with a downwardly-extending stem 14 extending through the bottom wall 6 and terminating upon the exterior thereof at the bottom surface in a single-turn flat coil 15 which serves as a foot or anchorage for the spring in each case.

Entirely covering and surrounding, and thereby concealing, the hollow mat or container 5 thus far described, is a fabric cover 16 having the sides

thereof at 17, 18 covering the upright end or peripheral walls 7, 8, etc., and having the bottom portion 19 covering the bottom 6 and the lower anchoring coils 15 of springs 13 so that the entire mat presents the appearance of a fabric object rather than one made of rubber or any other such material. Upon the upper surface of the mat and extending also through the cover 16 is a charging valve 20 which naturally extends through the upper wall 9 of the rubber container 5 to the internal chamber 11 in order to provide facilities for charging the mat with a new charge of powdered wax when the original charge has run low.

The action of the mat is evident from the fact that when a person steps on the same, the pressure of the foot will partly compress certain of the springs 13, 13 and depress the upper wall 9 of the wax container 5 within and thereby cause pulverized wax to rise through apertures 10, 10 and through the upper fabric 16 to make contact with the sole of a shoe applied to the fabric. If the shoe is dragged across the fabric a few times, the application of the wax will be reinforced to the desired extent, and as soon as the feet are removed from the mat, springs 13 will cause the upper wall 9 again to resume its parallel flat condition with respect to the bottom 6, ready for instant use again by the next person desiring to wax their shoes. A particular advantage of the invention is that while the floor may be partially waxed, which, of course, is desirable, yet the main portion of the wax serving the desirable functions involved in this case is to be applied to the shoes and not to the floor, and hence the desirable condition is thereby carried out by the person wearing the shoes thus waxed, and each person, therefore, is able to accommodate himself according to his own experience and taste.

Manifestly, variations may be resorted to and parts and features may be modified or used without others within the scope of the appended claims.

Having now fully described our invention, we claim:

1. An automatic wax-dispensing mat including a low substantially flat resilient container having a substantially horizontal top and bottom which are vertically spaced apart to receive the wax between them, the top of the container having a plurality of dispensing apertures, a plurality of compressible coil springs arranged between the top and bottom for maintaining the same resiliently spaced apart, each spring including a depending longitudinal stem extending through the bottom and a lateral substantially flat anchoring coil secured to the stem and engaging beneath the bottom, and a fabric envelope for the container and serving to conceal the latter and the perforations in the top, and a charging valve in the latter accessible through said fabric envelope for introducing powdered wax into the container.

a container of at least partly resilient material having a substantially flat bottom, peripheral walls extending upwardly from the edges of the bottom, a perforate flat top secured to the peripheral walls, a plurality of compression coil springs disposed between the bottom and top for resiliently supporting the latter in normal spaced parallelism with respect to the bottom, each spring having a depending stem extending through said bottom and terminating exteriorly upon the latter in an anchoring coil, a fabric envelope for the container serving to conceal the latter and the perforations in the top, and a charging valve in the latter accessible through said fabric envelope for introducing powdered wax into the container.

2. A wax dispensing mat, comprising a low substantially flat resilient container including a substantially horizontal top and bottom which are vertically spaced apart to receive the wax between them, the top of the container having a plurality of dispensing apertures, a plurality of compressible coil springs arranged between the top and bottom for maintaining the same resiliently spaced apart, each spring including a depending longitudinal stem extending through the bottom and a lateral substantially flat anchoring coil secured to the stem and engaging beneath the bottom, and a fabric envelope for the container and serving to conceal the same and cover the dispensing openings.
